UNITED STATES PATENT OFFICE.

ALONZO E. RHOADES, OF HOPEDALE, MASSACHUSETTS, ASSIGNOR TO DRAPER COMPANY,
OF HOPEDALE, MASSACHUSETTS, A CORPORATION OF MAINE.

WARP STOP-MOTION FOR LOOMS.

No. 909,822.

Specification of Letters Patent.

Patented Jan. 12, 1909.

Application filed January 11, 1908. Serial No. 410,336.

To all whom it may concern:

Be it known that I, ALONZO E. RHOADES, a citizen of the United States, and resident of Hopedale, county of Worcester, State of Massachusetts, have invented an Improvement in Warp Stop-Motions for Looms, of which the following description, in connection with the accompanying drawing, is a specification, like letters on the drawing representing like parts.

This invention relates to warp stop-motion apparatus for looms, wherein drop devices or detectors which control the stop-motion are hung upon and suspended from the warp-threads, the invention having for its object the production of novel means for limiting the upward movement or jumping of the detectors on their supports.

I have provided means whereby the limiting member or downhold may be slid manually into inoperative position to permit ready access to the detectors, and the downhold may be also lifted bodily from the loom without the use of a wrench or other tool.

The various novel features of my invention will be fully described in the subjoined specification and particularly pointed out in the following claims.

Figure 1 is a transverse sectional view of a sufficient portion of a loom, provided with a warp stop-motion embodying my invention; Fig. 2 is an enlarged rear elevation, centrally broken out, of the warp stop-motion mechanism; Fig. 3 is a left hand elevation of the apparatus shown in Fig. 2, with the downhold in operative position; Fig. 4 is a similar view but showing the downhold in its inoperative position; Fig. 5 is a section on the line 5—5, Fig. 2, looking to the right but with the downhold in inoperative position, and shown in dotted lines as about to be removed bodily from the loom; Fig. 6 is a top plan view, broken out, of the downhold.

The warp-stop-motion is shown as mounted on stands A^x, one on each loom side, between the whip-roll W and the harnesses H, H', Fig. 1, brackets 1 bolted to the stands having each an upturned web 2, which webs sustain a rod 3 on which are pivotally mounted apertured frames 4 into the apertures of which the lease-rods L and L' loosely extend. Said lease-rods divide the warp into two divisions w, w', and I have

shown herein two banks or series of drop devices or detectors d, each slotted longitudinally from its lower end at d' and being suspended from a single warp-thread, the two series of detectors being located between the lease-rods and being guided vertically by transverse supports 5, 5 arranged in parallelism and held at their ends on depending portions 6 of the brackets 1.

A double-stroke feeler f is mounted on a rock-shaft f supported in the bracket portions 6, and vibratile in a path below the detectors by any suitable or well known mechanism, a released detector in either series engaging and arresting the feeler to effect stoppage of the loom in well known manner.

The mechanism so far described forms no novel part of my present invention and is chosen for purposes of illustration.

Upon each of the webs 2 I adjustably secure, as by bolts 7, an elongated metallic plate 8 of sufficient length to extend across the ends of the lease-rods, limiting their end-wise movement, and at its front end each plate has formed upon it an upright ear 9 having an undercut notch 10, the flat upper edges 11 of the plates forming fixed supports for the downhold, to be described. A rock-shaft 12 is mounted in said plates at their rear ends, behind the detectors, and upon the projecting ends of the shaft I secure the hubs of upturned swinging arms 13, their upper ends extending above the plates and being shaped at 14 to form handles.

As shown in Fig. 2 a light spring 15 is coiled around the rock-shaft 12 and has one end secured to the adjacent plate 8, the other end being attached to a collar 16 fast on the rock-shaft, the winding of the spring being so arranged as to tend to throw the arms 13 forward. Rearward movement of the arms is limited by stops 17 on the plates 8, and as shown in Fig. 4 when the arms are against the stops they are almost directly above the rock-shaft, so that very little effort will move them forward.

In the present embodiment of my invention the downhold comprises an elongated sheet metal body 18 turned down at its front and rear edges to form flanges 19, the body being secured, as by rivets 20, Fig. 6, to end members 21, which are light castings, each being cut away to leave a shoulder 22 and at their rear portions widened and shaped to present open sockets 23. The flanges 19 em-

brace the front and rear edges of the end members, as shown in Fig. 6, and the latter rest upon the top edges 11 of the plates 8, the shoulders 22 abutting against the ends of 5 the notches 10 when the downhold is in its operative position, see Fig. 3, the overhanging portions of the ears 9 above the end members 21 serving to prevent any rising of the downhold. As shown in Fig. 1 the 10 body 18 of the downhold extends across the loom above the series of detectors *d*, so that their upward movement or jumping is effectually limited, with no possibility of the 15 disengagement of a detector from its warp-thread or the support 5.

The arms 13 enter loosely the sockets 23 of the end members of the downhold, and when the latter is operatively positioned shoulders 24 on the arms rest flat upon the 20 members 21, see Fig. 3, while the back portions 25 of the sockets 23 overhang shoulders 26 on the rear edges of the arms. The front edges of the sockets 23 are beveled, so that when the arms are swung upward into the 25 position shown in Figs. 4 and 5 the said edges will rest against the front edges of the arms, and the shoulders 26 turn under the parts 25, giving sufficient freedom of movement between the arms and the downhold to 30 permit the latter to be slid rearwardly along the tops of the plates 8 when the arms 13 are swung rearward by the operator.

When the downhold is in inoperative position, Fig. 5, the detectors of both series are 35 exposed so that free access may be had thereto, as will be manifest, but if for any reason greater freedom be desired, or if a new warp is to be put in, the operator can lift the downhold bodily, removing it entirely from 40 the arms, as shown by dotted lines Fig. 5.

Ordinarily it is supposed that the weaver will grasp one of the handles 14 and swing the arms 13 forward, after correcting a warp fault, to thereby return the downhold to 45 operative position. Should this be neglected, however, the downhold will be returned automatically to operative position, for as soon as the loom is started the vibrations will act in conjunction with the spring 15 to 50 turn the rock-shaft 12 and gradually throw the arms forward to operatively position the downhold. When the loom is at rest the force of the spring is not sufficient to swing the arms forward from the position shown 55 in Figs. 4 and 5.

Having fully described my invention, what I claim as new and desire to secure by Letters Patent is:—

1. In a warp stop-motion for looms, in 60 combination, a series of vertically-movable detectors each suspended from a warp-thread, a downhold to limit upward movement of the detectors, fixed supports on which the downhold is slidable and manu- 65 ally actuated means loosely connected with

and to slide the downhold along said supports into inoperative position.

2. In a warp stop-motion for looms, in combination, a series of vertically-movable detectors each suspended from a warp-thread, 70 a downhold to limit upward movement of the detectors, means to automatically and directly engage and prevent lifting of the downhold when moved to operative position, and manually actuated means 75 loosely connected with and to slide the downhold out of such engagement and into inoperative position.

3. In a warp-stop-motion for looms, in combination, a series of vertically-movable 80 detectors each suspended from a warp-thread, a downhold to limit upward movement of the detectors, and manually actuated means, detachably and loosely connected with and to slide the downhold into 85 inoperative position and permitting movement of the downhold relatively to said means.

4. In a warp-stop-motion for looms, in combination, a series of vertically-movable 90 detectors each suspended from a warp-thread, a downhold to limit upward movement of the detectors, the downhold having sockets at its ends, fixed supports to sustain the downhold in operative position, and 95 manually actuated means to slide the downhold into inoperative position, said means including pivotally mounted arms loosely entering the sockets of the downhold.

5. In a warp-stop-motion for looms, in 100 combination, a plurality of series of vertically-movable detectors, suspended from single warp-threads, a downhold adapted to extend above the detectors and limit upward movement thereof, fixed supports for 105 the downhold and provided with devices to engage the same and prevent it from rising, and swinging retracting members detachably connected with the downhold, to slide it along the fixed supports into inoperative 110 position.

6. In a warp-stop-motion for looms, in combination, a plurality of series of vertically-movable detectors, suspended from single warp-threads, fixed supports at the 115 ends of the series of detectors, a downhold adapted to be seated thereon to limit upward movement of the detectors, a rock-shaft behind the detectors, arms fixed on said rock-shaft and loosely connected with 120 the downhold, to slide the same rearwardly and permit ready access to the detectors, and a spring operatively connected with the rock-shaft to automatically insure return of the downhold to operative position when 125 the operation of the loom is resumed.

7. In a warp-stop-motion for looms, in combination, a plurality of series of vertically-movable detectors, suspended from single warp-threads, fixed supports at the 130

- ends of the series of detectors; a downhold comprising an elongated sheet-metal body, and rigid end members attached thereto, each end member having an open socket, 5 connected, pivotally mounted arms behind the detectors, and extended loosely into the sockets, to slide the downhold along the fixed supports into and out of operative position above the detectors, and means to effect the movement of the arms to operatively position the downhold.
8. In a warp-stop-motion for looms, in combination, a plurality of banks or series of vertically movable detectors each suspended from a single warp-thread, a downhold to limit upward movement of the de- 10
- 15
- tectors, manually actuated means to slide the downhold out of operative position, and a loose and detachable connection between said means and the downhold, whereby the latter may be lifted wholly free of said means when desired, said loose connection permitting relative movement of the downhold and said means when the downhold is moved into and out of operative position. 20 25
- In testimony whereof, I have signed my name to this specification, in the presence of two subscribing witnesses.
- ALONZO E. RHOADES.
